UNITED STATES PATENT OFFICE

CARL M. OLSEN, OF CHICAGO, ILLINOIS, ASSIGNOR TO A. J. JOHNSON & SONS FURNITURE CO., OF CHICAGO, ILLINOIS, A CORPORATION OF ILLINOIS

DESIGN FOR A CABINET FOR RADIO RECEIVING SETS

Application filed January 13, 1930. Serial No. 34,119. Term of patent 3½ years.

To all whom it may concern:

Be it known that I, CARL M. OLSEN, a citizen of the United States, residing at Chicago, in the county of Cook, and State of Illinois, have invented a new, original, and ornamental Design for Cabinet for Radio Receiving Sets, of which the following is a specification, reference being had to the accompanying drawing, forming part thereof.

The figure is a perspective view of a cabinet for radio receiving sets showing my new design.

I claim:

The ornamental design for a cabinet for radio receiving sets, as shown.

CARL M. OLSEN.
